[57] CLAIM

The ornamental design for an axillary crutch, as shown and described.

DESCRIPTION

FIG. 1 is a perspective view of an axillary crutch showing our new design;

FIG. 2 is front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of a crutch shaft is for illustrative purposes only and forms no part of the claimed design.
